UNITED STATES PATENT OFFICE.

HOMER S. BERGER, OF MUNCY, PENNSYLVANIA.

GATE-VALVE

1,134,811.

Specification of Letters Patent.

Patented Apr. 6, 1915.

Application filed May 9, 1914. Serial No. 837,477.

To all whom it may concern:

Be it known that I, HOMER S. BERGER, a citizen of the United States, residing at Muncy, in the county of Lycoming and State of Pennsylvania, have invented new and useful Improvements in Gate-Valves, of which the following is a specification.

This invention relates to improvements in gate valves.

10 In carrying out the present invention, it is my purpose to provide a gate valve which will embody, among other features, a casing having a fluid passage formed therethrough, a seat formed therein across the passage, a gate movable into and out of the passage to obstruct and open the latter and coacting with said seat and comprising two longitudinal sections and a wedge block interposed between said sections and movable 20 simultaneously therewith in the opening and closing of the valve and independently thereof to force the sections into binding engagement with the seat whereby a fluid tight joint will be effected, and to release said 25 sections.

It is also my purpose to provide a valve of the class described which will embrace the desired features of simplicity, efficiency and durability, which may be manipulated 30 with ease and convenience and which may be installed and maintained at a minimum expense.

With the above and other objects in view, the invention consists in the construction, 35 combination and arrangement of parts hereinafter set forth in and falling within the scope of the claim.

In the accompanying drawings; Figure 1 is a view in side elevation of a gate valve 40 constructed in accordance with the present invention. Fig. 2 is a vertical longitudinal sectional view therethrough. Fig. 3 is a vertical cross sectional view therethrough. Fig. 4 is a horizontal sectional view 45 through the valve. Fig. 5 is a sectional view on the line 5—5 of Fig. 2. Fig. 6 is a collective view of the gate showing the component parts thereof in perspective. Fig. 7 is a fragmentary top plan view of the gate.

50 Referring now to the drawings in detail, 1 designates a casing formed longitudinally with a fluid passage 2 and having the opposite ends thereof equipped with outwardly projecting circumferential flanges 3,3 where- 55 by the casing may be connected in a line of pipe. Surmounting the casing 1 and pref-

erably formed integral with the upper wall thereof is a bonnet 4 arranged approximately centrally of the casing and of a width corresponding with the similar dimension of the casing. In the present instance, this bonnet is composed of a bottom inner section 5 and a top or outer section 6 and the confronting edges of the sections 5 and 6 are formed with outwardly extending flanges 7 provided with bolt holes through which are passed securing bolts 8 whereby the sections are held in bonnet formation. The top wall of the casing 1 approximately centrally of the bonnet is formed with a transverse slot 9, while the inner surfaces of the opposite side walls contiguous the extremities of the slot 9 are formed with vertical grooves 10 communicating at the lower extremities with a transverse groove 11 formed in the inner face of the lower wall of the casing. The opposite side walls of the grooves 10 and the latter walls taper downwardly and merge into the side walls of the groove 11, the groove 11 being relatively narrow as compared with the width of the slot 9 so that a tapering seat is formed.

Movable into and out of the seat to close and open the passage 2 is a gate 12 comprising, in the present instance, two longitudinal sections 13, 13 tapering downwardly in cross section and having the outer faces thereof adapted to seat against the adjacent walls of the slot 9, grooves 10 and groove 11, and a wedge block 14 interposed between the confronting faces of the sections 13, 13 and capable of movement with the sections in the opening and closing of the valve and independently of the sections to force the latter into binding engagement with the walls of the seat and release the same. Formed on the upper ends of the sections of the gate 12 approximately centrally thereof are upwardly extending lugs 15 having the upper ends thereof bent at right angles to themselves as at 16, and extending toward each other, such lugs co-operating with each other to form a bonnet, while extending upwardly from the top end of the wedge block 14 are similar lugs 17 spaced apart and forming a bonnet.

Rotatably mounted within the upper end of the bonnet 4 and extending upwardly therefrom is a tubular valve stem section 18 having the lower end thereof threaded 110 interiorly as at 19 and threaded into the stem section 18 and depending therefrom

within the bonnet 4 is an exteriorly threaded stem section 20 having the lower end thereof equipped with a head 21 disposed within the non-circular bonnet formed by the lugs 15. Passed through the axially alining bores of the stem sections 18 and 20 is a stem 22 having the upper end thereof terminating above the adjacent extremity of the stem section 18 and the lower end formed with a non-circular head 23 disposed within the bonnet formed by the lugs 17 on the upper end of the wedge block 14. In the present instance, the lower extremity of the stem 22 is screwthreaded and engages the threads formed in the bore of the stem section 20 so that when the stem 22 is rotated in one direction the wedge block 14 will be moved downwardly to spread the gate sections 13, 13, while when the direction of rotation of the stem 22 is reversed the wedge block will be elevated to permit the gate to contract. Fixed to the upper end of the stem section 18 is a hand wheel 23, while secured to the upper extremity of the stem 22 is a hand wheel 24. The stem sections 18 and 20 constitute a telescoping valve stem and when the section 18 is rotated in one direction under the action of the hand wheel 23, the threaded stem section 20 moves into the section 18 thereby elevating the sections 13 and wedge block 14 of the gate 12, the stem 22 sliding upwardly within the bores in the telescoping sections of the valve stem. When the direction of rotation of the telescopic stem is reversed the section 20 moves downwardly within the bonnet thereby sliding the gate into the seat and across the passage 2 through the casing 1. Succeeding the seating of the gate, the stem 22 is rotated to lower the wedge block 18 whereby the outer faces of the sections of the gate bind against the adjacent walls of the seat to form an effective fluid tight joint whereby leakage around the gate is eliminated. When it is desired to elevate the gate to open the valve the stem 22 is revolved under the action of the hand wheel 24 to elevate the wedge block 14 so that the sections of the gate will be relieved of the influence of the wedge. The telescopic section is now actuated to elevate the gate and the latter moved out of the passage 2 whereby the fluid controlled by the valve is free to flow. The upper end of the bonnet 4 is preferably equipped with a stuffing box 25 surrounding the stem section 18 and forming a fluid tight joint, while the hand wheel 23 of the telescopic stem is also equipped with a stuffing box 26 whereby a fluid tight joint between the telescopic stem and the wedge block stem is formed.

The confronting walls of the seat and

gate are preferably lined with wear resisting packing material 27 in order to increase the efficiency of the valve and prolong the life thereof, while a pet cock 28 is threaded into the bottom wall of the groove 11 in order that any air or water therein may be drained off when necessary or desired.

From the foregoing description taken in connection with the accompanying drawings, the construction, mode of operation and manner of employing my improved gate valve will be readily apparent. It will be seen that I have provided a gate valve wherein the gate may be readily moved to closed and open positions and locked in closed position.

The opposite side walls of the bonnet 4 are preferably formed with vertical grooves 29, 29 forming continuations of the grooves 10 in the side walls of the casing 1 and acting as ways to receive the opposite ends of the gate so that as the latter is moved into the bonnet in the opening of the valve movement thereof out of alignment with the seat is avoided.

While I have herein shown and described one preferred form of my invention by way of illustration, I wish it to be understood that I do not limit or confine myself to the precise details of construction herein described and delineated, as modification and variation may be made within the scope of the claim without departing from the spirit of the invention.

I claim:

In a gate valve, a casing having a passage therethrough and formed with a valve seat transversely thereof and having vertical grooves formed in the opposite side walls thereof contiguous the valve seat, a gate movable into and out of said passage and seat and comprising two sections, a wedge between said sections and having the opposite ends thereof slidably disposed within said grooves, means for actuating said wedge independently of said sections to bind the latter against the adjacent walls of the seat, means for moving said sections and wedge simultaneously to open and close the valve, a lining of wear resisting material on the confronting faces of said valve and seat, and a bonnet surrounding said casing and having the opposite side walls thereof formed with grooves alining with the first-mentioned grooves to receive said gate when the latter is moved out of engagement with the valve seat.

In testimony whereof I affix my signature in presence of two witnesses.

HOMER S. BERGER.
